UNITED STATES PATENT OFFICE.

SAMUEL LIPPERT, OF EAST CLEVELAND, OHIO.

CONDENSING AND VACUUM PUMP.

1,339,402.

Specification of Letters Patent.

Patented May 11, 1920.

Application filed August 21, 1915. Serial No. 46,709.

To all whom it may concern:

Be it known that I, SAMUEL LIPPERT, a citizen of the United States, and resident of East Cleveland, in the county of Cuyahoga and State of Ohio, have invented certain new and useful Improvements in Condensing and Vacuum Pumps, of which I hereby declare the following to be a full, clear, and exact description, such as will enable others skilled in the art to which it appertains to make and use the same.

This invention relates to a condensing pump and more particularly to a condensing pump of the type used on steam heating systems for drawing the condensed steam from the radiators and pumping such condensation back to the boiler to be again converted into steam.

The object of the present invention is to provide means for automatically drawing the condensed steam from the radiators and forcing such condensation back to the steam boiler.

In the accompanying drawing wherein I have shown an illustrative embodiment of my invention, Figure 1 is a vertical sectional view of my pump and Fig. 2 is a detail view of the valve sleeve which admits steam and a cold water spray alternately to the pump chamber.

Describing the various parts by reference characters, F indicates the pump chamber casing which has an upper inlet opening E adapted to receive the exhaust line from the radiators (not shown), and a lower discharge opening G which is connected, through a check valve W, to the boiler (not shown). A pipe I for admitting steam, and a pipe H for admitting a spray of cold water are fitted in axial alinement into the top and bottom of the chamber respectively, and connected by a union R. The pipe I is provided on one side with a steam port N through which steam escapes into the chamber and the pipe H is provided at its upper end with a series of small perforations or jet openings O, through which the water escapes as a fine spray into the chamber.

A sleeve valve K is slidable over the union R to alternately open and close openings N and O. Pivoted at p—p, on the horizontal bar Q are the rock arms or levers P—P which are forked at their inner ends to embrace the sleeve valve K, as indicated at P'—P'. The union R is slotted as shown at s to allow vertical movement of the con-

necting pin S, which pivotally fastens the levers P—P and sleeve valve K together. This movement of sleeve valve K serves to alternately open port N thereby closing the jet openings O and open openings O thereby closing port N. The outer ends of the levers P—P are pivotally connected to a yoke M which is provided near its upper end with the float stops m—m. A float L, which rises and falls within the yoke M according to the water level in the chamber F engages at the upper limit of its movement with the stops m—m and at the lower limit of its movement with the lower bar m' of said yoke.

In operation, the pipe I is connected to the steam supply from the boiler and the pipe H is connected to any suitable source of cold water. The exhaust line from the radiators is connected to the opening E and the opening G is connected through the check valve W to the water supply of the boiler. Steam passes through the radiators and is condensed and flows by gravity into the chamber F. As the chamber fills, the float L rises until it strikes against the stops m—m, which serves to depress the valve K and open the steam port N.

Live steam under pressure from the boiler then enters and forces out the condensed water through check valve W back to the water supply in the boiler. The admission of steam to the chamber serves to equalize the pressure on opposite sides of the check valve W whereby water flows by gravity and steam pressure thereupon, into the boiler and when the float has fallen with the water level, the float will strike against the lower bar m' of the yoke and the valve will be operated by the rock arms to rise and close the steam port and uncover the spray openings O. A spray of cold water will then be projected into the steam filled chamber which condenses the steam and creates a vacuum. The vacuum and force of gravity will cause a flow of condensation from the radiators into chamber F where the series of operations will be repeated as long as steam is available from the boiler.

While I have described my pump as used with a heating system it will be understood that it is not limited to the same except as set forth in the appended claims, and that it can be used wherever steam is available and it is desired to pump liquids.

Having described the invention what I

claim as new and desire to secure by Letters Patent is:

1. In a condensing pump the combination with a condensing chamber, of an inlet pipe 5 for live steam, an inlet pipe for cold water, said pipes being alined with each other and provided with lateral openings, and a sleeve valve slidingly movable over said openings and operating to alternately open and close

10 the same.

2. In a condensing pump, the combination with a condensing chamber, of an inlet pipe for live steam and an inlet pipe for cold water, said pipes being alined with each 15 other and provided with lateral openings, a sleeve valve slidingly movable over said openings and operating to alternately open and close the same, and float operated means

within said chamber for operating said valve.

3. In a condensing pump of the character described, the combination, with a chamber, of a supply pipe for steam communicating with said chamber and a supply pipe for cold water communicating with said chamber, a valve common to both of said pipes within said chamber and adapted alternately to open the one and close the other, and a float within said chamber and connected to said valve.

In testimony whereof I hereunto set my hand this nineteenth day of August, 1915.

SAMUEL LIPPERT.

In presence of—

VICTORIA BEZOSKA,

FRANK H. EWING.
